A. OLLER

INCUBATOR

Filed April 16, 1924

UNITED STATES PATENT OFFICE.

ALBERT OLLER, OF WALDRON, ARKANSAS.

INCUBATOR.

Application filed April 16, 1924. Serial No. 706,937.

The object of my invention is to render to the greatest degree possible the reliable operation of incubators in regard to the matter of periodically turning the eggs, and of periodically ventilating the incubator, and to do these things by automatic mechanism which while being simple and not costly to install may be depended upon to perform the operations required. In what I now consider the most satisfactory embodiment of my invention, such embodiment has a construction which will secure all of the objects or advantages noted but this does not mean that I restrict myself to that embodiment or to the presence in an incubator of all of the features of construction appearing therein as hereinafter described. My invention consists in whatever is described by or is included within the terms or scope of the appended claims.

In the annexed drawings:

Fig. 1 is a perspective view of an incubator embodying my invention.

Fig. 2 is a detail sectional view.

The incubator shown in the drawings has a box-like casing, 10, with a hinged door at the front to give access to the interior thereof and which is provided with the usual heating means such as a lamp and a damper that includes a vertically swinging rod, 11, mounted on a post or support, 12, on the top of the casing, the damper rod, 11, rocking up and down in response to changes of temperature within the incubator and I make use of such movement of the damper rod to give an alarm when the temperature rises above or falls below the temperature which it is desired shall be maintained in the incubator so that attention may be given to correct the condition which has resulted in objectionable change of temperature. The alarm which I consider most satisfactory is an electric bell, 13, which besides other advantages may be conveniently located at any desired point so that for example the incubator may be placed in the cellar or basement of the house and the bell located in the kitchen or dining room or other place where its alarm will be heard at once. The bell is in an electric circuit which includes a battery, 14, and two contact devices situated on opposite sides of the pivotal support, 12, of the damper rod, 11, the circuit being closed by the damper rod through one contact device when the temperature rises and closed through the other contact device when the

temperature falls. The two contact devices are alike each comprising normally separated terminals, 15, of copper wire which are attached to the top of the casing by porcelain or other insulating cleats, 160, the extremity of each terminal beneath the rod, 11, being formed into a ring, 16, directly beneath the damper rod, 11, so as to assure contact of the terminals by the damper rod. 60 By branched wires, 17, both contacts use the same battery, 14, and the single bell, 13. After the incubator has been heated to the proper temperature the copper terminals forming each contact device are adjusted 70 which can readily be done by bending the wire so that their coiled extremities, 16, will be at that position below the damper rod, 11, as to be touched by the damper rod when that change of temperature in the incubator has taken place at which it is desired the alarm shall be given. 75

The egg support is in the form of a disk, 18, which may be made of beaver board, which is provided with holes, 19, each of a size to contain and support an egg so that say about one-fourth of the egg protrudes below the bottom of the disk which being attached to a vertical shaft, 20, occupies a vertical position. The shaft, 20, at its lower 80 end within the casing rests in a bearing, 21, and is supported at its upper end by a bearing, 22, upon the top of the incubator casing and reaching above the top of the casing it has fixed to it a bevel gear wheel, 23. 85 Meshed with the beveled gear, 23, is a pinion, 24, on a horizontal shaft, 25, which is connected at one end to a spring motor, 26, which conveniently and preferably is a clock, the driving connection between the 90 shaft, 25, and the clock being conveniently made by means of the winding key or stem, 27, of the clock, the end of the shaft and the stem or key being fastened together. Between the clock and the pinion, 24, the shaft, 25, has a bearing, 28, mounted on the top of the incubator casing and such bearing and also the bearings of the vertical shaft, 20, are preferably ball-bearings so as to reduce friction to the minimum. As the shaft, 25, 100 through the clock connection described makes a revolution every six hours and the proportion of the pinion, 24, to the gear, 23, is such that the gear, 23, makes one revolution while the pinion makes five revolutions, 105 the egg carrying disk, 18, will make one revolution every thirty hours. Of course, I 110

do not limit myself to any one rate of revolution of the parts just mentioned.

The long axis of each egg receiving hole, 19, is radial to the shaft, 20, with the smaller end of the hole innermost, the hole being egg shape and the egg is placed in the hole with the smaller end toward the central shaft, 20. The portion of the egg projecting beneath the disk, 18, is brought by the revolution of the disk in contact with a friction device, 29, in the form of a strip of wood covered with cloth that lies immediately beneath the disk, 18, so that as the disk, 18, revolves the frictional contact of each egg in succession with said friction device will partially rotate the egg on its longitudinal axis and with the gearing proportioned as has been above described each egg will be partially rotated on its axis, preferably through a quarter turn, every fifteen hours and, of course, during the intervals of contact with the friction device, 29, will be quiescent or at rest as to rotation on its axis.

A convenient way of attaching the egg carrier, 18, to the shaft, 20, is to thread the shaft, 20, for a portion of its length to receive nuts, 30, and washers, 31, above and below the carrier disk, 18, to clamp the disk at the desired position. I show in the drawings but one carrier disk but obviously more than one could be applied to the same shaft, 20.

The shaft, 20, is preferably mounted in its bearings so that it may be lifted to raise the disk carrier, 18, which may be desirable to do to render more comfortable or easier getting access to the eggs or hatching chickens.

Besides driving the egg carrier, 18, from the clock driven shaft, 25, I utilize said shaft to control ventilation of the incubator automatically. This I do by providing on the shaft, 24, a radial arm or crank, 32, which by the revolution of the shaft is brought in contact with a projection, 33, on the upper side of a slide, 34, placed in parallel guides, 35, upon the top of the casing over an opening, 36, in the latter so that by movement of the slide to and fro such opening may be covered and uncovered and thus a ventilator device provided. The slide, 34, is yieldingly held in a position to close the opening, 36,

by a spring, 37, attached at one end to a fixed point on the incubator top and at the other end to the slide, and the crank or arm, 32, moves the slide in opposition to the pull of the spring. Preferably the projection, 33, which is engaged by the crank or arm, 32, is an antifriction roller. It will be seen that with regular periodicity at every revolution of the shaft, 25, and during a portion of such revolution the engagement of the crank, 32, with the roller, 33, will slowly uncover the ventilating opening, 36, and in the case of the clock arrangement shown in the drawings such opening will take place slowly during thirty minutes.

The clock or spring motor may conveniently be fixed in position on the top of the incubator casing by spring arms, 38, which clamp it upon opposite sides.

What I claim is:

1. An incubator comprising a casing, means within the casing for supporting eggs with the peripheries thereof exposed and for rotating the eggs, comprising relatively stationary and rotatable members, a vertical shaft supporting the rotatable member and extending through the casing top and accessible for grasping by the hand for moving said shaft and the member carried thereby vertically, and means to rotate the shaft.

2. An incubator comprising a casing, a vertical shaft extending through the top of the casing and accessible for grasp by the hand to lift the shaft, an egg carrier upon said shaft, said shaft and carrier being vertically movable and means to rotate the shaft.

3. An incubator comprising a casing, a vertical shaft, an egg carrier mounted upon the shaft within the casing, a spring motor, a shaft receiving motion from said motor mounted upon the top of the casing, a gear connection between said shaft and said vertical shaft, a movable ventilator member mounted on the top of the casing over an opening therein, a spring holding said member normally in closed position and a crank on the motor driven shaft that moves said member in opposition to the spring.

In testimony whereof I hereunto affix my signature.

ALBERT OLLER.
